UNITED STATES PATENT OFFICE.

WALTER C. BAUER, OF KANSAS CITY, MISSOURI.

DRIVING MECHANISM FOR WASHING MACHINES.

1,405,657.

Specification of Letters Patent. Patented Feb. 7, 1922.

Application filed November 18, 1919. Serial No. 339,079.

To all whom it may concern:

Be it known that I, WALTER C. BAUER, a citizen of the United States, residing at Kansas City, in the county of Jackson and State of Missouri, have invented certain new and useful Improvements in Driving Mechanism for Washing Machines, of which the following is a specification.

My invention relates to improvements in driving mechanism for washing machines, wherein the washing of clothes and other articles is accomplished by placing the clothes in a cylinder which revolves in hot water containing soap or other detergents, said cylinder making one or more revolutions in one direction, then automatically reversing and making one or more revolutions in the opposite direction to agitate the water and expose all parts of the clothes or other articles being washed to the cleansing effect of such water.

The objects of the invention are, first, to produce a power driven washing machine, in which reversal of the cylinder is positively effected.

Second, to eliminate the operator from liability of accident usually involved in operating machines of this type.

Third, to minimize the amount of power required to operate the machine; and fourth to eliminate all gearing inside the body of the machine.

Other objects of the invention will hereinafter appear, and in order that said invention may be fully understood, reference will now be had to the accompanying drawings, in which:

Fig. 1 is a side elevation partly in section of a washing machine constructed in accordance with the invention.

Fig. 2 is a broken vertical section on line II-II of Fig. 1.

Fig. 3 is a broken elevation of a portion of the frame and gear casing.

Fig. 4 is a broken horizontal section on line IV-IV of Fig. 1.

Fig. 5 is an enlarged broken vertical section on line V-V of Fig. 3.

Fig. 6 is an enlarged horizontal section on line VI of Fig. 1.

In carrying out the invention, I employ a suitable tub 2, mounted on a frame 4 embodying legs 6.

8 designates a cylindrical agitator rotatably mounted within the tub 2 and

adapted to receive the clothes and other articles to be washed. Said cylinder 8 is mounted upon trunnions 10 journaled in bearings on the frame 4. One of the trunnions 10 is provided at its outer end with a large fixedly-mounted bevel gear 12, intermeshing with small oppositely-disposed bevel gears 14 and 16 loosely mounted upon a shaft 18, journaled in bearings 20 in a gear case 22, secured to one side of the frame 4 and provided with a removable cover 23. The shaft 18 is provided near one end with a fixedly mounted bevel gear 24 intermeshing with a bevel gear 26, fixedly-mounted upon a shaft 28 which may be utilized for driving a wringer, not shown.

The shaft 18 is driven by a fixedly-mounted worm wheel 30 intermeshing with a worm 32, fixedly mounted upon a shaft 34 journaled in bearings 36 and provided at one end with a pulley 38 adapted to be driven by a belt and motor, not shown. The bevel gears 14 and 16 are provided with clutch members 40 and 42, respectively, which are alternately engaged and driven by a clutch member 44 having a groove and feather connection 46 with the shaft 18. Coil springs 47 are interposed between the ends of the clutch member 44 and the clutch members 40 and 42, for a purpose which will hereinafter appear.

The clutch member 44 is controlled by a lever 48, fulcrumed in the gear case 22 on a stud 50. The lever 48 is provided intermediate its ends with an antifriction roller 52, projecting into a peripheral groove 54 in the clutch member 44.

The lower end of the lever 48 is provided with an antifriction roller 56, for engagement with a plunger 58, reciprocably mounted in a boss 60 depending from the gear case 22. The plunger 58 has a conical upper end and is pressed upwardly into engagement with the roller 56 by a spring 62, arranged in the lower portion of the boss 60 and adjusted vertically by a set screw 64, threaded in the lower end of the boss 60.

66 designates a link pivotally connected at one end to the upper portion of the lever 48 and at its opposite end to a crank 68 mounted to oscillate upon a shaft 70, journaled in the gear case 22 and provided with a fixedly-mounted cog wheel 72 intermeshing with a pinion 74, formed integral with a fixedly-mounted cog wheel 72 intermeshing with a pinion 74, formed integral

with or otherwise secured to the hub of the large bevel gear wheel 12. The cog wheel 72 is provided with a wrist pin 71, to oscillate the crank 68, as will hereinafter appear.

5 78 designates a pin for securing the lever 48 in neutral position when it is desired to stop the cylinder 8 without stopping the motor. Said pin 78 is slidably mounted in a tubular housing 80 on the case cover 23, 10 and has an enlarged terminal 82 at its inner end and a crank 84 fixed to its outer end. A coil spring 86 interposed between a shoulder in the housing 80 and the enlarged terminal 82 on the pin 78, tends to push 15 said pin into an opening 88 in the lever 48 and thus secure the latter in neutral position, as above-mentioned. A lug 90 is formed on the crank 84 and adapted to enter a recess 92 in the adjacent end of the housing 80 to let the pin 78 enter the opening 88 in the lever 48. The pin 78 is withdrawn from the opening 88 by rotating the crank 84 a quarter of a revolution to cause the lug 90 to ride out of the recess 92 and withdraw the pin 78 as above-mentioned.

The operation is substantially as follows: The lever 48 is released from neutral position and then automatically shifted to the right or left by upward movement of the 30 plunger 58. Motion is then imparted to the drive pulley 38, which in turn drives the worm 32, the worm wheel 30, and the shaft 18. Assuming that the clutch member 44 was shifted into engagement with the clutch member 40, by the lever 48, said clutch member 40 will then drive the small bevel gear 14, which in turn drives the cylinder 8 through the intermediacy of the large bevel gear 12 and the trunnion 10 on which said 35 bevel gear 12 is fixedly mounted. As the large bevel gear 12 rotates it carries the pinion 74 therewith, which in turn drives the cog wheel 72. Assuming that the cog wheel 72 is caused to rotate in the direction 40 of the arrow, Fig. 1, it carries the wrist pin 71 around into engagement with the left side of the crank 68 and pushes the same to the right. As the crank 68 swings to the right it pushes the lever 48 in the same direction 45 through the intermediacy of the link 66 until the clutch member 44 is disengaged from the clutch member 40 and the roller 56 reaches the apex of the plunger 58, whereupon it is carried beyond said apex 50 by the momentum of the cylinder 8. The instant the roller 56 passes the apex of the plunger 58 the same is instantly pushed upwardly by the spring 62 and completes the throw of the lever 48, causing it to shift the 55 clutch member 44 quickly into engagement with the clutch member 42 of the bevel gear 16. Said bevel gear 16 then drives the cylinder 8 in a reverse direction through the intermediacy of the large bevel gear 12 and 60 the trunnion 10. The bevel gear 12 carries 65

the pinion 74 in a reverse direction and causes it to reverse the direction of travel of the cog wheel 72, so that the same will carry the wrist-pin 71 around into engagement with the right side of the crank 68, moving it to the left. As the crank 68 swings to the left, it swings the lever 48 therewith through the intermediacy of the link 66 until the clutch member 44 is disengaged from the clutch member 42 and 70 reaches the apex of the plunger 58, across which it is carried by the momentum of the cylinder 8. The foregoing operations are repeated until the lever 48 is secured in neutral position by the pin 78. 75

From the foregoing description it will be readily understood that I have produced a driving mechanism washing machine embodying the advantages above pointed out and while I have shown and described the preferred form of the invention I reserve the right to make such changes in the construction, combination and arrangement of parts as properly fall within the spirit and scope of the claims. 80

Having thus described my invention, what I claim and desire to secure by Letters Patent, is:

1. In a washing machine, a tub, a cylinder mounted in said tub, a large bevel gear to rotate said cylinder in reverse directions, a pair of small bevel gears constantly in mesh with said large bevel gear at opposite sides of its axis, a rotary shaft on which said small bevel gears are loosely mounted, a clutch on the rotary shaft to alternately lock the small bevel gears on said shaft, an oscillatory lever to release said clutch and cause it to alternately lock the small bevel gears on the shaft, a handle to said lever whereby it may be manually operated to move the clutch to neutral position, means for engaging said lever to hold the same stationary and stop the rotation of the cylinder, a link to swing said lever through a part of each stroke, a crank to actuate said link, means geared to the cylinder to oscillate said crank, and means for completing the strokes of said lever. 90

2. In a washing machine, a tub, a cylinder mounted in said tub, a large bevel gear to rotate said cylinder in reverse directions, a pair of small bevel gears constantly in mesh with said large bevel gear at opposite sides of its axis, a rotary shaft on which said small bevel gears are loosely mounted, a clutch on the rotary shaft to alternately lock the small bevel gears on said shaft, an oscillatory lever to release said clutch and cause it to alternately lock the small bevel gears on the shaft, a link to swing said lever through a part of each stroke, a crank to actuate said link, means geared to the cylinder to oscillate said crank, comprising a wrist-pin to actuate said crank, and a wheel geared 95

to the cylinder and carrying said wrist-pin, and means for completing the strokes of said lever.

3. In a washing machine, a tub, a cylinder mounted in said tub, means for driving said cylinder in reverse directions embodying an oscillatory lever, a pin to lock said lever in neutral position, a tubular housing secured to the tub and through which said pin operably extends, a spring tending to force the pin into engagement with the lever, and a

handle fixed to the pin and provided with means to coact with the tubular housing in withdrawing the pin from the lever when said handle is rotated. ¹⁵

In testimony whereof I affix my signature, in the presence of two witnesses.
